C. C. BEAM

BOWL OR SIMILAR ARTICLE

Filed Jan. 12, 1928

Inventor
Charles C. Beam,

By Dodge and Denos,

Attorneys

UNITED STATES PATENT OFFICE.

CHARLES C. BEAM, OF CUMBERLAND, MARYLAND.

DESIGN FOR A BOWL OR SIMILAR ARTICLE.

Application filed January 12, 1928. Serial No. 24,835. Term of patent 14 years.

To all whom it may concern:

Be it known that I, CHARLES C. BEAM, a citizen of the United States, residing at Cumberland, in the county of Allegany and State of Maryland, have invented a new, original, and ornamental Design for a Bowl or Similar Article, of which the following is a specification, reference being had to the accompanying drawing, forming part thereof.

The figure is a perspective of a bowl or similar article showing my new design.

I claim:

The ornamental design for a bowl or similar article as shown.

CHARLES C. BEAM.
